UNITED STATES PATENT OFFICE.

WILLIAM F. CUSHMAN, OF BOSTON, MASSACHUSETTS.

CLIP FOR PENS OR PENCILS.

1,321,893.

Specification of Letters Patent. Patented Nov. 18, 1919.

Application filed July 24, 1917. Serial No. 182,447.

To all whom it may concern:

Be it known that I, WILLIAM F. CUSHMAN, a citizen of the United States, residing at Boston, county of Suffolk, State of Massachusetts, have invented an Improvement in Clips for Pens or Pencils, of which the following description, in connection with the accompanying drawing, is a specification, like characters on the drawing representing like parts.

This invention relates to a clip for holding pens, pencils and similar articles in the pocket of a garment, and particularly to a clip of that well-known type which embodies a split band adapted to encircle the pen or pencil, and a retaining finger extending from the band and adapted to overlie the outside of the pocket in which the pen or pencil is placed thereby to frictionally retain the pen or pencil in the pocket.

The object of my invention is to provide a clip of this type which is provided at the end of its retaining finger with a novel bearing portion which is constructed to present a rounded bearing surface for engagement with the outside of the pocket of the garment.

In order to give an understanding of my invention, I have illustrated in the drawings a selected embodiment thereof which will now be described, after which the novel features will be pointed out in the appended claim.

Figure 1 is a view of my improved clip affixed to a fountain pen;

Fig. 2 shows the blank from which the device is made;

Fig. 3 shows the first step in giving the blank the desired shape;

Fig. 4 is an enlarged section on the line 4—4, Fig. 3;

Fig. 5 is an enlarged view of the lower end of the holding finger after it is completed;

Fig. 6 is a section on the line 6—6, Fig. 5.

The complete device comprises a holding finger 1 which is preferably somewhat resilient and which is formed at its lower end with a novel bearing portion adapted to engage the outside of the pocket of the garment. This finger 1 may be secured to the fountain pen in any usual way. I have herein shown it as provided at its upper end with the split resilient ring or band 2

which is adapted to surround and frictionally engage the pen or pencil 3, as usual in devices of this class.

In making my improved pen and pencil holder, I take a blank of the shape shown in Fig. 2, and which is provided with the finger 1, and the portion 4 from which the split band 2 is formed. The blank is formed at the lower end of the finger with the two circular portions 5 and 6 that are connected by the neck 7. In forming my improved clip, I subject the finger to the action of forming dies which are shaped to give each of the circular portions 5 and 6 the shape shown in Figs. 3 and 4, that is, each of the circular portions 5 and 6 is bent or shaped so that the central portion 9 thereof has a concavo-convex shape, and the peripheral or marginal portion 10 at each side is shaped to present a narrow flange. This central portion 9 is preferably given a semi-spherical shape. After the semi-spherical portions 5 and 6 have been thus formed, the portion 6 is folded over onto the portion 5 to bring the flanges 10 together and to bring the semi-spherical portions 9 into alignment with each other. After the portion 6 is thus folded over against the portion 5, said two portions are squeezed between dies to firmly press the flanges 10 together.

The completed device thus made presents at the end of the finger 1 a ball-shaped portion represented by the two semi-spherical portions 9 and the double flange 10 encircling the ball portion. The ball portion furnishes a rounding surface which rests against the outer face of the garment when the device is used for holding a pen or pencil in the pocket. The device presents no projections which are liable to catch on the garment when the pencil is inserted into the pocket, and the ball-shaped portion not only is neat in appearance, but is effective in accomplishing the desired result of holding the pencil in place.

The device is simple and inexpensive to make as it is formed entirely from a single blank which is bent into the proper shape and there is no assembling of separate parts as is the case where the clip is made of two or more parts.

I claim:

A pen and pencil clip presenting a resilient holding finger having integral there-

with at its lower end two oppositely-disposed concavo-convex semi-spherical portions, each of which has a peripheral flange occupying a diametrical plane, said flanges being co-extensive and integrally connected at a point opposite the finger and also overlying each other whereby the semi-spherical

portions form a hollow ball surrounded by a diametrical flange of double thickness occupying the same plane as the finger.

In testimony whereof, I have signed my name to this specification.

10

WILLIAM F. CUSHMAN.
